E. C. WHITE,
ELECTRICAL CONNECTING AND SUPPORTING DEVICE,
APPLICATION FILED APR. 9, 1920.

1,364,419.

Patented Jan. 4, 1921.

WITNESS

UNITED STATES PATENT OFFICE.

ERNEST CANTELO WHITE, OF NEW YORK, N. Y., ASSIGNOR TO ELECTRIC OUTLET COMPANY, INC., OF NEW YORK, N. Y., A CORPORATION OF NEW YORK.

ELECTRICAL CONNECTING AND SUPPORTING DEVICE.

1,364,419.

Specification of Letters Patent.

Patented Jan. 4, 1921.

Application filed April 9, 1920. Serial No. 372,383.

To all whom it may concern:

Be it known that I, ERNEST CANTELO WHITE, a citizen of the United States, residing in the borough of the Bronx of the city of New York, in the State of New York, have invented certain new and useful Improvements in Electrical Connecting and Supporting Devices, of which the following is a specification, reference being had to the accompanying drawing, forming a part hereof.

In the following mentioned applications filed by the present applicant there are shown and described several different embodiments of an improved supporting device for electrical appliances in which connection with a source of current supply is made upon application of the supporting element to a receptacle or the like:

- 20 Ser. No. 350,688 filed January 10, 1920;
" " 350,689 " " 10, "
" " 350,690 " " 10, "
" " 352,087 " " 17, "
" " 363,419 " March 5, "
- 25 The principal object of the present invention is to provide in an electrical conducting and supporting device an electrical receptacle which has entrance openings to receive the straight blades of an attachment plug 30 and the conducting and supporting members of a fixture supporting plug separately, and terminals to frictionally engage the said blades and the said members, the receptacle having bearing surfaces inaccessible to the 35 blades for the support of the fixture. In the illustrated embodiment there is shown such a receptacle for the straight horizontal blades for a tandem attachment plug, and for the straight parallel blades of a standard 40 attachment plug.

Other objects of the invention will appear as the description proceeds, the illustrated construction having incorporated therein several practical features of improvement 45 over the devices shown in said copending applications.

In the drawing:

Figure 1 is a view in vertical section of an improved receptacle showing an electrical 50 appliance supported thereon through an improved supporting plug, parts of the receptacle being removed in the interest of clearness.

Fig. 2 is a view in front elevation of the 55 improved receptacle showing one arrange-

ment of slots therein for receiving the arms of the improved supporting plug and the terminals of attachment plugs.

Fig. 3 is a view in horizontal section through an outlet box in which is supported 60 the improved receptacle, part of the receptacle being shown in plan and part being broken away to show the application of an attachment plug thereto.

Fig. 4 is a view in elevation of the improved supporting plug.

Fig. 4^a is a view in perspective of the plug.

Figs. 5 and 6 are detail views of one of the contact plates employed in the improved 70 receptacle, Fig. 5 indicating one of the straight blades of a standard attachment plug in the groove of the plate and in frictional engagement with the terminal.

Before describing in detail the practical 75 features of construction which are considered of importance in the improved structure, so much of the coöperating elements will be described as will be necessary for an understanding of one means for carrying 80 out the principal improvement which consists in bringing into combination with electrical connecting and supporting devices for electrical appliances, means for connecting ordinary attachment plugs of any 85 approved form to one element of the improved electrical connecting and supporting devices. In carrying out this phase of the invention it will be manifest that no limitations are to be imposed on the specific 90 character of the supporting receptacle nor on the specific character of the supporting plug, since the invention is much broader than the application of attachment plugs to receptacles of the specific form constituting 95 generally the subject matter of the above mentioned applications.

As shown in Fig. 1 the ordinary outlet box *a* has supported therein a flush receptacle, indicated generally at *b*, and this 100 receptacle has in its front wall slots *b'* to receive the arms *c* of a supporting plug *c'* for an electrical appliance. When the plug *c'* is applied to the receptacle *b* by introducing the arms *c* into the slots *b'*, electrical connection is simultaneously established 105 between said arms and the source of current supply which may be derived through leads *d*. The broadest aspect of the invention contemplates the incorporation in some 110

such receptacle, as is indicated at b , in combination with the means for supporting and connecting electrical appliances, such as are illustrated by the plug c' with its arms c , means for receiving and connecting attachment plugs, such as e , with the source of current supply d . As shown in the drawing, the face of the receptacle b is provided with additional slots b^2 into which may be introduced the terminals e' of an attachment plug such as e . Into the slots b' might be introduced an attachment plug having terminals which are disposed in parallelism to one another and so spaced as to enter said slots. For convenience a tandem arrangement of slots b' , b^2 has been illustrated and these slots will receive terminals arranged in the relationship now most commonly employed in attachment plugs, as will be appreciated by one skilled in the art. However, the invention is in nowise limited to the particular form or relation of the slots to receive the terminals of attachment plugs, since it is broad enough to include in combination with such slots as b' to receive supporting arms for an electrical appliance, additional slots at any part of the receptacle to receive the terminals of attachment plugs, the underlying thought of the invention being to retain in such a receptacle all of the functions which it now ordinarily performs with attachment plugs and to provide for the performance of the additional function of receiving supporting arms for an electrical appliance.

Having now pointed out the substantial breadth of the invention, the means illustrated in the accompanying drawing for practising it will be described in detail.

The receptacle b is made of three insulating blocks b^3 , b^4 , b^5 , normally held together by through-bolts f . Between the side walls of the central block b^4 and the outer blocks b^3 and b^5 may be secured metallic terminal plates g , h , of generally symmetrical form. A description of one of the plates, such as g illustrated in Figs. 5 and 6, will apply to both. This plate has formed therein a slot g' which is preferably curved, for a reason which will later appear, and carries a terminal screw g^2 to which may be secured one of the leads d to energize the plate. The mouth of the slot g' registers with the slot b' , so that when one of the arms c is introduced through the slot b' it will pass along the groove g' . On the face of the plate g is secured a spring terminal g^3 which is of such form as to receive the terminal arms e' of the type of attachment plug e for which the receptacle is designed. With the type of plug shown in Fig. 3 the spring arms g^3 receive terminal arms e' which are disposed generally in the same horizontal plane. When the arms e' of the attachment plug e pass through the slots b^2

in the face of the receptacle they engage the terminal g^3 and are thereby energized. Adequate support for the plug e is given as in the usual type of flush receptacle, no stress being imposed on the plug. An attachment plug e having generally vertically disposed arms arranged in parallelism might be applied to the receptacle by introducing such arms through the slots b' . The arms one of which is indicated at e^2 would then extend along the grooves g' and be energized by engagement therewith or by engagement with the side edges of the terminals g^3 , as best indicated in Figs. 5 and 6.

It will be understood, of course that the insulating blocks b^3 , b^4 , b^5 which, when bolted together, constitute the body of the block b , may be so cut or molded as to afford adequate space for the portions of the contact plates g , h , and their accessories, although it is desirable to have the fit between the plates and the various blocks snug so as to hold the parts against relative displacement. Around the center block b^4 may be passed a strip i which terminates in lugs i' which may be secured by screws l to the outlet box a , for the support of the receptacle within the box. However, other means for supporting the receptacle b in the box may be employed. The strap i , if desired, may be bent over the face of the central block b^4 and then reversely bent upon itself to cover the extending lugs i' and the reversely bent portion be apertured to receive screws l by which an ornamental wall plate m may be supported in position. All of these details, however, may be changed to conform to best practice taking into account compactness, appearance, strength and expense.

The block c' is formed of two insulating blocks c^2 , c^3 secured together by means of bolts m . One of the blocks c^3 is provided with slots through which pass the curved conductor arms c and these arms are carried with the plate c^4 to which is secured a binding screw n for the conducting wire o of the electrical appliance indicated generally at o' . Two wires and two binding screws n are, of course, employed, these screws being applied to the separate conductor arms c , c . Around the blocks c^2 , c^3 may pass a metallic reinforcing and binding plate p extended at one point to form a hook p' , the reverse face of which may be beveled. The screws n may pass through the plate p in the interest of additional strength and security. The appliance o' may carry on its base a transverse bridge o^2 which, when the appliance is to be engaged with the supporting plug c' is passed downwardly and engaged with the beveled face of the hook p' .

From the description given it is evident that when the improved connecting and sup-

porting devices are to be employed, the supporting plug *c'* having had its conductor arms *c* connected electrically with the wires *o* of the appliance *o'* is engaged with the 5 receptacle *d* by introducing the arms *c* into the slots *b'*. The arms *c* pass rearwardly along the grooves *g'*, etc. of the plates *g*, *h*, thereby becoming energized and creating a strong and rigid support for the appli- 10 ance. The appliance is then engaged, as by means of the bridge *o*², with the hook *p'* and the plug *c'* is thereby locked in engagement with the receptacle against accidental removal or dislodgment. This is all in ac- 15 cordance with the principles described in the copending applications hereinbefore identified. When an attachment plug of any form is to be connected electrically with a source of current supply, it is evident that 20 the improved receptacle *b* affords a convenient connecting medium therefor. The plug *e* may have its conductors *e'* introduced through the slots *b*² into engagement with the terminals *g*³, or if the plug have parallel 25 terminals such terminals may enter the slots *b'* and be energized by engagement with the plates *g*, *h*, or with the terminals *g*³ carried thereon. As pointed out hereinbefore slots for attachment plugs having other re- 30 lation and form than the tandem form shown herein may be incorporated in the improved receptacle and the details of the interior structure of the receptacle might be changed as desired.

35 I claim as my invention:

1. An electrical receptacle formed with an entrance opening to receive the straight blade of an attachment plug, also the conducting and supporting member of a fixture 40 supporting plug, of similar cross-section, and including within the receptacle terminal means to frictionally engage the said blade and the said member, the said receptacle and terminal means including bearing 45 surfaces for the said member having portions spaced apart from positions accessible to the said blade.
2. An electrical receptacle formed with an entrance opening to receive the straight 50 blade of an attachment plug, also the conducting and supporting member of a fixture

supporting plug, of similar cross-section, and including within the receptacle a terminal plate formed with bearing surfaces perpendicular to the plate for the said member, 55 the said plate carrying means to frictionally engage the said blade and the said member, the said bearing surfaces having portions spaced apart from positions accessible to the said blade. 60

3. An electrical receptacle formed with entrance openings to receive, separately, the straight blades of an attachment plug and the curved conducting and supporting members of a fixture supporting plug and 65 including within the receptacle terminals to frictionally engage the said blades and the said members, the said receptacle and terminals including bearing surfaces for the sides of the said members nearest to the 70 fixture supporting plug.
4. An electrical receptacle formed with two entrance openings to receive, separately, the straight, flat blades of an attachment plug and the curved, flat conducting and 75 supporting members of a fixture supporting plug, and including within the receptacle terminal plates formed with bearing surfaces for the sides of the said members nearest to the fixture supporting plug, the 80 said terminal plates including means to frictionally engage the said blades and the said members.
5. An electrical receptacle formed with two parallel entrance openings to receive, 85 separately, the straight, flat blades of an attachment plug and the curved, flat conducting and supporting members of a fixture supporting plug, and also formed with entrance openings to receive the horizontal 90 blades of an attachment plug, and including within the receptacle terminals to frictionally engage said blades and the said members, said receptacle being provided with common terminals for said blades and 95 said members, and said receptacle and terminals including bearing surfaces for the said members spaced apart from positions accessible to the said blades.

This specification signed this 26th day of 100
March A. D. 1920.
ERNEST CANTELO WHITE.
